UNITED STATES PATENT OFFICE.

JACOB M. LEE, OF HOUSTON, TEXAS.

STOCK-GUARD.

SPECIFICATION forming part of Letters Patent No. 588,868, dated August 24, 1897.

Application filed March 5, 1897. Serial No. 626,132. (No model.)

To all whom it may concern:

Be it known that I, JACOB M. LEE, a citizen of the United States, residing at Houston, in the county of Harris and State of Texas, have 5 invented certain new and useful Improvements in Stock-Guards; and I do hereby declare the following to be a full, clear, and exact description of the invention, such as will enable others skilled in the art to which it app- 10 pertains to make and use the same.

My invention relates to improvements in stock-guards; and it consists of certain novel features hereinafter described and claimed.

Reference is had to the accompanying drawings, in which the same parts are indicated by the same letters throughout the several views.

Figure 1 represents a perspective view of a portion of a single-track railroad with my 20 improved stock-guard. Fig. 2 represents a perspective view of one of the sections of my improved stock-guard as detached from the track; and Fig. 3 represents a longitudinal vertical section on a somewhat larger scale 25 than is used in the other figures, showing the details of construction of the stock-guard.

C C represent the railway-tracks, and D D the ties. The stock-guard is made up of a plurality of sections, one between each pair 30 of tracks and one on the outside thereof. Where there is a single track, the stock-guard will be made in three sections, as shown in Fig. 1, and where there is a double track the stock-guard will be made in four sections, one 35 section between each pair of tracks and one on the outside of the road-bed, and so on where there are a larger number of tracks.

Each section of the stock-guard is composed of two end plates A, provided with down- 40 wardly-projecting tongues a, adapted to fit roughly between the cross-ties. Between these two end plates A a plurality of inverted V-shaped plates B are secured, preferably by means of flanges b, as shown most clearly in 45 Fig. 3. These bent plates B consist of two legs b' and b², one longer than the other. The longer leg projects downward between the cross-ties beneath the overhanging lip of the other leg b². This is shown most clearly in 50 Fig. 3. Thus it will be seen that a passage is left for the flow of water from the longer legs between them and the cross-ties, while

the projecting lip of the shorter legs is adapted to engage the ankle of the animal endeavoring to cross the track, the foot of the said animal sliding downward and its ankle catching in the said overhanging lip of the short leg b². 55

In order to secure the sections of the stock-guard in place, they are provided with downwardly-projecting flanges b³, which are bolted 60 to the cross-ties, as shown in Fig. 3. Now when it is desired to remove the stock-guard, as for repairing the road-bed or the like, the bolts holding these flanges b³ are withdrawn and the section of stock-guard is temporarily 65 removed, as indicated in Fig. 2.

In most forms of stock-guard now in use the various parts are attached to the road-bed in such a way that it is extremely difficult and inconvenient to remove the same, and it frequently becomes necessary to repair the road-bed, tracks, or the like at the points occupied 70 by these stock-guards.

It will be obvious to any one versed in such matters that the herein-described stock-guard 75 is a cheap, light, simple, and durable device which may be readily applied and as readily removed when desired.

Having thus described my invention, what I claim, and desire to secure by Letters Patent of the United States, is—

1. A stock-guard composed of a plurality of separate sections, each section comprising two end plates, with tongues adapted to project down between the cross-ties of the road-bed, and inverted-V-shaped plates, having one leg shorter than the other adapted to rest on top of the cross-ties, and having the outer edge of the shorter leg projecting beyond the face of the cross-tie, substantially as described. 85

2. In a stock-guard for use on railroads, the combination with the end plates A provided with tongues a adapted to project down between the cross-ties of the road-bed, of the 95 flanged plates B secured to the said end plates A and provided with the long legs b' and the short legs b², the said short legs projecting over the lower edge of the longer legs, and being adapted to project beyond the edge of the 100 cross-ties, substantially as described.

3. A stock-guard composed of a plurality of separate sections, each section comprising two end plates, with tongues adapted to pro-

- ject down between the cross-ties of the road-bed, and inverted-V-shaped plates, having one leg shorter than the other adapted to rest on top of the cross-ties, and having the outer edge of the shorter leg projecting beyond the face of the cross-tie, with flanged ends b^3 to each section adapted to be secured to the cross-ties by spikes or bolts, substantially as described.
- 10 4. In a stock-guard for use on railroads, the combination with the end plates A provided with tongues a adapted to project down between the cross-ties of the road-bed, of the flanged plates B secured to the said end plates

A and provided with the long legs b' and the short legs b^2 , the said short leg projecting over the lower edge of the longer leg, and being adapted to project beyond the edge of the cross-ties, with flanged ends b^3 to each section adapted to be secured to the cross-ties by spikes or bolts, substantially as described.

In testimony whereof I affix my signature in presence of two witnesses.

JACOB M. LEE.
